FASTENING CLIP

Frank R. Chester, Santa Monica, Calif.

Application May 6, 1949, Serial No. 2,498

Term of patent 7 years

(Cl. D17—3)

To all whom it may concern:

Be it known that I, Frank R. Chester, a citizen of the United States, residing at Santa Monica, in the county of Los Angeles, State of California, have invented a new, original, and ornamental Design for Fastening Clip, of which the following is a specification, reference being had to the accompanying drawings, forming a part thereof, in which:

Fig. 1 is a perspective view in elevation of a fastening clip showing my new design, the view being taken from the front and partly from one side;

Fig. 2 is a side elevational view; and

Fig. 3 is a perspective view, taken from one side and partly from the front, the clip being partially compressed with the end open.

I claim:

The ornamental design for a fastening clip, substantially as shown and described.

FRANK R. CHESTER.
